UNITED STATES PATENT OFFICE.

CHARLES A. BRAUN, OF REDDING, CALIFORNIA.

WATCHMAKER'S INSTRUMENT.

No. 918,822.

Specification of Letters Patent.

Patented April 20, 1909.

Application filed December 2, 1907. Serial No. 404,710.

To all whom it may concern:

Be it known that I, CHARLES A. BRAUN, a citizen of the United States, residing at Redding, in the county of Shasta and State of California, have invented certain new and useful Improvements in Watchmakers' Instruments, of which the following is a specification.

My invention relates to improvements in watch-gages, and has for its object the provision of a simple and efficient device for use in the assembling of watches to indicate the proper distance which the stem of the watch case should project into the case in order to properly engage and mesh with the winding and setting mechanism of the movement.

Another object of my invention is the provision of means for holding and gripping the stem to prevent turning of the same and allow removal of the crown. In this way, the stem may be held to permit removal of the crown and access to the pendant sleeve, which sleeve may be adjusted until the stem projects into the case the proper distance, the device indicating when the proper adjustment is finally attained.

With these and other objects in view, my invention comprises broadly, means for indicating the proper length for the stem of a watch, and means for gripping and holding said stem.

My invention also consists of a watchmaker's instrument embodying certain other novel features of structure, arrangement and combination of parts substantially as herein disclosed and illustrated in the accompanying drawings, in which:

Figure 1, is a face of the device used in connection with an ordinary pendant watch case, parts being shown in section. Fig. 2, is a detail view of the gripping means for holding the stem of the case. Fig. 3, shows enlarged detail views of the indicating mechanism of the device. Fig. 4, is a broken sectional view of the spring pressed button for holding the gage in place in a watch case. Fig. 4^a, is a broken top view of the upper portion of Fig. 2. Fig. 5, is a detail view of a modified form of the invention.

This invention is related very closely to my companion case executed and filed of even date herewith, both inventions being for the same purposes and accomplishing the same ends though by different means.

The main or body portion of the device consists of a flat disk or back plate or support

1, having an annular upraised or thickened rim 2, the whole adapted to be received in the watch case. This back plate would be made in different sizes to fit in the different standard size watch cases. The annular rim of the back plate has a seat or recess 3, therein to receive the head 4, of the plunger or slide 5, the plunger having a longitudinal slot 6, therein, receiving the guiding and confining screw 7. The slide thus has a limited sliding movement upon the face of the back plate or support. Either the angular and flattened head of the slide or the rim of the back plate as shown in Fig. 4^a has a keyhole slot 8, 70 formed therein, to receive the squared lower end of the stem of the watch case.

When the instrument is in use, the round or enlarged portion of the keyhole slot ordinarily receives the end of the stem and the stem may be freely turned. When it is desired to hold the stem against turning, as for instance when the crown is to be removed, the back plate or support is given a slight twist, which causes the stem to be engaged in the narrower portion of the keyhole slot and there held against turning. The crown may then be readily removed, the stem remaining stationary.

In order to properly engage and mesh with the movement, the stem should project into the case a certain predetermined distance. As the slide is engaged and depressed by the stem the proper adjustment for the stem could be indicated by providing a scale adjacent the edge of the slide and providing the slide with suitable marks or a mark to register on the scale and indicate the proper length of the stem for winding and setting, but I prefer to pivot a pointer 9, to one side of the slide, the pointer having a slotted angular arm 10, in the slot of which is engaged the pin 11, carried by the lower end of the slide. The pointer registers upon the scale 12, which is usually provided with the markings "Wind" and "Set" for indicating such proper positions for the stem. The spring 13, serves to hold the head of the slide in engagement with the end of the stem. A grooved or cut away portion 14, in the rim of the supporting plate, as best shown in Fig. 4^a, assists in guiding the stem to proper engagement with the head of the slide, the upper edge of the back plate being inserted in the watch case first, the rim thereby engaging underneath the stem and the stem being received in the cutaway 14 in the rim to guide

the stem to the slide. A spring pressed button 15, mounted in the recess 15', in the rear, edge of the supporting plate is adapted to frictionally engage the interior of the watch case and hold the gage in place therein. The gage is also provided with finger holds 16, for handling the same.

In use, the device is placed in the empty watch case, the stem of the case being guided to engagement with the head of the slide. The slide is depressed by the stem causing the pointer to indicate upon the scale. If the stem is of the proper length for both the winding and setting positions, the pointer will so indicate upon the scale and no adjustment of the stem is necessary, but if the stem is either too long or too short, the pointer will so indicate. The device is then given a slight twist or rotary movement in the case, which movement causes the squared end of the stem to become wedged in the narrower portion of the keyhole slot and the stem is locked against turning. The crown may then be removed from the stem and the pendant sleeve may be turned to adjust the projection of the stem into the watch case. The pendant sleeve is thus adjusted until the pointer shows that the stem is of the proper length. If so desired, the keyhole or wedging slot for holding the stem may be formed direct in the rim of the supporting plate and the slide may have a flat head to be engaged by the stem. Other forms of indicating mechanism may also be employed, as for instance, the one shown in Fig. 5. Here the slide has a series of teeth or rack 17, along one edge which mesh with the segmental pinion 18, on the head of the pointer 19, the pointer being pivoted at 20, to one side of the slide and adapted to register upon the scale 21. In this instance, I have shown the slot for holding the stem as formed direct in the rim of the supporting plate at 22, and the slide as having a plane head 23, to be engaged by the stem. The operation of this form of gage is practically the same as of the one first described. In all forms of the invention herein shown, the pivotal head of the pointer is disposed adjacent the side of the plunger and has connection at such side with the plunger. From the above description taken in connection with the drawings, the operation and advantages of my invention will be readily understood and appreciated, and it will be obvious that I have produced an inexpensive and practical device which fully and satisfactorily accomplishes all the objects herein set forth.

I claim:

1. A gage for indicating the proper stem length for watches and the like instruments comprising a back plate to be received in the watch case, a slotted plunger having a head to be engaged by the stem, fastening means passing through the slot in the plunger for securing the same and permitting sliding movement thereof, and indicating mechanism operated by the plunger.

2. A gage for indicating the proper stem length for watches comprising a back plate to be inserted in a watch case, a slotted depressible plunger having a head to be contacted by the end of the stem, a spring forcing the plunger outward, means passing through the slotted portion of the plunger for slidably securing the plunger in place, and indicating means operated by the plunger.

3. A watchmaker's instrument comprising a back plate to be received in a watch case, friction means carried by the back plate for holding the same within the case, means carried by the back plate for holding the watch stem against rotation, a slotted plunger, means slidably confining the plunger to the back plate, a spring holding the plunger in engagement with the stem, and indicating means operated by the plunger.

4. A device of the character set forth comprising a back plate to be received in a watch case, a plunger slidably mounted on the back plate and adapted to be engaged by the stem of a watch, the back plate having means for guiding the stem to engagement with the plunger, an indicating pointer mounted on the back plate and an angular projecting portion on the pointer connecting the pointer to the plunger, and a spring forcing the plunger outward.

5. A watchmaker's instrument comprising a supporting member having means for receiving and holding a watch stem and means for guiding the stem to engagement with such receiving and holding portion, a depressible plunger mounted on the supporting member to be engaged by the stem, a pointer pivoted upon the supporting member, an angular member on the pointer connecting the pointer to the plunger, the supporting member having a scale provided with indications upon which the pointer is adapted to register, a spring tending to hold the plunger outward, and grasping means for handling the supporting member.

In testimony whereof I affix my signature in presence of two witnesses,

CHAS. A. BRAUN.
